UNITED STATES PATENT OFFICE.

ROBERT MIEHLE, OF CHICAGO, ILLINOIS.

MEANS FOR HOLDING AND ADJUSTING PRINTING-PLATES.

1,288,645.

Specification of Letters Patent. Patented Dec. 24, 1918.

Application filed February 26, 1917. Serial No. 150,868.

To all whom it may concern:

Be it known that I, ROBERT MIEHLE, citizen of the United States, residing at Chicago, in the county of Cook and State of Illinois, have invented a certain new and useful Improvement in Means for Holding and Adjusting Printing-Plates, of which the following is a full, clear, concise, and exact description.

10 My invention relates to devices for clamping and positioning stereotype, electrotype, and other printing plates in such manner that the plates may be adjusted or registered on the base with great nicety, and it has 15 more especial reference to that class in which the base is provided with a plurality of undercut grooves or channels in its surface for retaining the plate holding and adjusting hooks or clamps. These grooves or 20 channels are necessarily narrow and are only deep enough to accommodate the mechanism of the plate-adjusting devices, and for obvious reasons the entire clamp mechanism must be below the printing surface of the 25 plate so as not to be inked by the inking rollers.

This invention has for its primary object, to provide a plate holder having a drop-in member adapted to be turned in an undercut 30 groove of the base to engage said drop-in member with the undercut portions of the groove together with means, preferably extending longitudinally of the groove, engageable with the plate holder and a side 35 of said groove to prevent said plate holder from turning to disengage said drop-in member from the undercut portion of the groove, this means being adapted to allow adjustment of said plate holder longitudinally 40 of said grooves, and in the preferred embodiment of the invention, as hereinafter described, this means comprises a screw screw-threaded into said plate holder and having a head engageable with the base at various 45 points to afford a positive adjustment of the plate holder; and to provide a plate holder of the above described character actuating in a diagonally arranged groove having the drop-in member engageable with the side of 50 the undercut portion of the groove to coöperate with a means for adjusting the plate holder longitudinally of the groove to clamp the plate and to afford a wedging action of the plate holder against the plate whereby 55 the resistance of the plate angularly to the

groove is converted into resistance parallel to the groove and the adjustment means so that no side strain is placed on the adjustment means to cause excessive wear thereon; and to provide a device of the above 60 described character which provides a maximum amount of slow powerful adjustment and which may be inserted or removed from the groove at any point and which when inserted is positively held within said 65 groove.

I will explain my invention more fully by reference to the accompanying drawing showing the preferred form of hook of my invention and one use thereof, the drawing 70 illustrating the adaptation of such hook to a flat form base for a flat bed press, though the hooks of my invention are obviously adapted to be used in connection with any suitable form support known to those familiar with the art such as form bed bases of rotary presses. In the drawing Figure 1 is a plan view illustrating a part of a base and a plurality of printing plate sections assembled therewith by the hooks of my invention; Fig. 2 is an end elevation of the rigidly connected plate holding hook member and drop-in member without the hook adjusting means; Fig. 3 is a view on line 3—3 of Fig. 2; Fig. 4 is a plan view of the structure illustrated in Fig. 2; Fig. 5 is a view in side elevation of the structure appearing in Fig. 4; Fig. 6 is a view of the structure shown in Fig. 5 assembled with the base and in connection with which the positioning tool is 80 illustrated; Fig. 7 illustrates the structure of Fig. 6 with hook adjusting means added; Fig. 8 is a view on line 8—8 of Fig. 1; and Figs. 9 and 10 illustrate certain formations of the hook which are desirable when particularly narrow margins are to be secured; Fig. 11 is an enlarged partial side elevation of the adjustment screw in operative connection with its driving tool as hereinafter 90 described.

Like parts are indicated by similar characters of reference throughout the different figures.

The base 1 is shown as being flat for use in a flat bed press. It is curved in the case 105 of a rotary press. This base is provided with a plurality of parallel diagonal grooves 2 which are undercut, desirably upon each side, to make them of T-shape. Each side margin of each groove is provided with 110

notches 3. The printing plate structure is, in the embodiment of the invention illustrated, formed of a plurality of plate sections 4, 5, 6, etc. With reference to Figs. 1 and 8, the adjacent margins of adjacent plates 4 and 5 are provided with angular undercut grooves for receiving correspondingly shaped jaws of a plate engaging hook member 7. The margin of the plate 5 which is adjacent the plate 6 is provided with an outset beveled edge while the adjacent margin of plate 6 has an undercut groove, the adjacent edge portions of the plates 5 and 6 receiving the correspondingly shaped jaws of another plate engaging hook member 7. The right hand edge of plate 6 is outwardly beveled similarly to the beveling of the right hand edge of plate 5 and is engaged by a correspondingly shaped jaw of another plate engaging hook member 7. In Fig. 1, other plate sections 8, 9 and 10 are illustrated, edges of these plates and the adjacent edges of the adjacent plates 4, 5 and 6 being engaged by other plate holding hook members 7 of other plate hooks. In Fig. 1, the left hand edge of the plate section 4 is illustrated and this edge is outwardly beveled similarly to the right hand edge of plate 6 and is engaged by a plate holding hook member 7 to another plate hook. Each plate hook comprises a plate holding hook member 7 and a drop-in member 11 that are substantially rigidly connected, as by means of a cylindrical connecting member 12 which is nearer one end of the drop-in member 11 than the other so that such drop-in member has a long end and a short end as illustrated in Fig. 3. The plate holding hook member 7, however, desirably has its central portion connected with the connecting member 12. As illustrated, the drop-in member 11 is longer than the width of the top of the groove 2 and is of a width that will enable this drop-in member to lodge within the groove when this member is placed lengthwise of the groove. The plate holding hook member 7 of each hook is illustrated as being sufficiently long to extend across the top of a receiving groove 2. After the drop-in member has been placed lengthwise of a groove and has been deposited therein the hook structure is given a turn to engage the ends of the drop-in member with the undercut portions of the grooves. The plate holding hook member 7 and the drop-in member 11 are desirably formed in one integral piece with the connecting member 12 so that as the drop-in member is turned the plate holding hook member is also turned, turning movement being continued until the long end of the drop-in member 11 engages a side of the undercut portion of the receiving groove 2 whereupon the plate holding hook member, owing to its rigid relation 65 with the drop-in member, would be approxi-

mately in position to engage the plate that it is to hold. The platehooks that are interposed between the plates 4 and 8, 5 and 9, 7 and 10, and 4 and 5, are movable longitudinally of the grooves receiving them to enable them to be adjusted in position but are not shown as being provided with any adjusting mechanism connected therewith, these particular hooks being employed as spacers between adjacent plate sections of a 75 form section and operating merely to hold the plates down on the base in proper relation. The plate holding hook members 7 of these spacing hooks may be of different widths to suit different desired margins between plate sections. The plate hooks shown in engagement with the left hand edge of plate section 4 (Fig. 1), the adjacent edges of plate sections 5 and 6 and the right hand edge of plates 6 are illustrated with hook 80 holding and positioning means connected therewith for maintaining the drop-in member in position within the undercut portions of the receiving groove. This means, in these latter hooks, also constitute registering 85 means for effecting plate registering movement of these plate hooks. The registering and plate hook holding means is inclusive of a drop-in member 13 that is connected with its hook and is receivable within the 90 notches or pockets 3 to position the hook in the receiving groove by maintaining the drop in member 11 with its long end in engagement with the adjacent side of the undercut portion of the receiving groove. 95 Where the hook holding means is also a registering means the drop in member 13 preferably constitutes the head of a screw 14 which is receivable in the threaded horizontal opening 15 in the connecting member 100 12. Each of the hooks may have its connecting member 12 formed with a horizontal threaded opening 15 so that it may be either a mere plate holding spacing hook when it is unprovided with a registering 110 screw 14 or may be readily converted into a registering hook when provided with such screw. The assembly of the registering screws with the hook is effected after the hook is dropped in and turned approximately to a plate holding position, in which position the threaded opening 15 is properly aligned with the receiving groove 2 to receive the corresponding screw 14 which desirably has a reduced end 16 to guide the 115 screw into the hole 15, the hook being pushed against the screw to introduce the small end 16 of the screw into the opening 15 whereafter the screw head 13 is turned to effect desired threaded engagement between the 120 screw and the threaded opening 15. The registering hook member 7 may have its side that is adjacent the screw head 13 cut away as indicated at 7¹ (Fig. 1) and undercut at 7² (Fig. 2) to allow said member 7 to 130

be very closely approached to said screw head and partially to overlie the screw head. To increase the speed with which the screw 14 may be assembled with a plate hook after 5 the drop-in members and the screw and plate hook have been properly placed in relation to each other in a receiving groove 2, the rear end face of the screw is provided with a tool engaging gear formation 13¹ which 10 comprises a plurality of radial slots 13² disposed angularly to one another, the face 13³ of said formation being concave to decrease the depth of the slots at the center, see Figs. 7 and 11. These slots are engageable by the 15 cross 10¹ upon an end of the tool 19, which comprises a plurality of driving formations disposed in radial relation with one another to be engaged with respective slots 13². The end 19¹ of the tool 19 is rounded and has a 20 greater degree of curvature than said concave face so that when the end 19¹ of the tool is engaged with said face with its axis inclined to that of the screw, those driving formations, which are substantially perpendicular to a plane passing through both axes, 25 engage the respective slots only at the center, at which point, it will be noted, the slots are shallow, thus allowing clearance so that there is no interference when the tool is rotated though this limited engagement of 30 said driving formations retains the tool in central engagement with the gear formation. While so inclined the driving formation which is disposed adjacent the plane passing 35 through the axes of the screw and tool, and on the side of the lesser angle defined by said axes, constitutes the drive, the opposite driving formation and its slot being entirely out of engagement. See Fig. 11. The tool is 40 maintained in proper longitudinal position by the engagement of the end 19¹ with the bottoms of the slots. When a screw has been assembled with a hook the head 13 of the screw (constituting a drop-in member), 45 through the intermediation of the screw, prevents the drop-in member 11 from turning and leaving the undercut portions of the groove 2 that receive the drop-in member 11 whereby the assembly of the hook and base 50 is maintained.

It will be observed that the notches or 55 pockets 3 are retainers for the screw heads 13 and confine these screw heads to fixed planes of rotation and afford bearing surfaces therefor as said heads are turned. The bottoms of the receiving grooves also constitute bearing surfaces for said screw heads. By this construction screw heads of comparatively large diameter may be employed in 60 which tool receiving holes 17 may be formed for receiving the screw head engaging end portion 18 of an adjusting tool 19. This tool end 18 may also be inserted in holes 20 that are provided in the tops of the hook 65 members 7 to aid in the positioning of the

hook members and their withdrawal from the base. Where the screw heads 13 are of such diameter that upper portions thereof project above the upper surface of the base 1 the bottom faces of the plates are desirably grooved (as indicated at 21 Fig. 8) to accommodate the upper portions of such screw heads. Some of the plate holding hook members 7 may each have but one jaw, as for example those which engage the outer 70 edges of outer plate sections. Other plate holding hook members 7 may each be provided with double jaws as for example those which are interposed between the plate sections 4 and 8, 4 and 5, and 5 and 6, the hooks 75 which are interposed between the plate sections 5 and 6 being also used as adjusting spacing hooks to define fixed positions for those spacing hooks between form sections. In Fig. 1 the plate sections 6 and 10 are in 80 one form section and the plate sections 4, 5 8 and 9 are in another form section, these two form sections being separated by fixed spacing hooks such as those illustrated between the plate sections 5 and 6. The spacing 85 hooks that are interposed between the plate sections of a form section need not have any means forming parts thereof for fixing them in connection with the base as these particular plate holding hooks should be allowed to 90 automatically position themselves as the plate sections are moved and adjusted.

Where the registering hook or spacing hook is interposed between plate sections that 95 are to be very closely approached the structure shown in Figs. 9 and 10 is preferred. In 100 this construction the plate holding hook member is made very narrow and is desirably of triangular shape in cross section with the base of the triangle at the top of said member. The plate section that is adjacent the higher side of the connecting member 12 is provided with a conforming recess 12¹ to enable this plate to be engaged by the adjacent side of the adjacent plate holding member 7. A plate hook as constructed in accordance with Figs. 9 and 10 may be merely 105 a spacing hook or it may be equipped with the adjusting mechanism 13, 14 to constitute 110 it an adjustable hook.

It will be noted that, when a plate hook of the drop-in construction described is used in conjunction with a groove running diagonally of the form, which diagonal arrangement is the approved construction for reasons which it is unnecessary to state, the line of stress is disposed angularly to the groove and the adjustment screw which is disposed parallel therewith. This stress would, if unresisted, bend the adjustment screw or displace the same so that it would lie angularly to the groove, which would increase as the pressure is increased. Either of these conditions would result in excessive wear on the screw and its related parts. Engagement 115 120 125 130

of the connecting member 12 with the corresponding portion of the groove could be utilized to prevent this, but this engagement has its limitations as applied to a hook of the 5 above described drop-in construction for obvious reasons, particularly where, as herein illustrated and described, that portion of the groove which is engaged by said connecting member 12 is notched. In order to prevent 10 this excessive wear and to afford a rigid construction I have extended and formed the end of the drop-in member 11, which extends from the point at which pressure is applied to the hook by the adjustment screw, *i. e.*, the 15 connecting member 12, in the general direction of the pressure exerted by the screw, to engage the opposing side of the undercut portion of the groove whereby a wedging action is caused by said plate hook between the 20 plate and said opposing side of the undercut portion of the groove. Thus, as pressure is applied by the screw after the plate holding hook member 7 has engaged with the plate, the resistance of the plate is met by the screw 25 and by said extended end of said drop-in member 11 in its engagement with the opposing side of the groove, and the angular resistance of the plate against the pressure applied by the adjustment screw is converted 30 into resistance running parallel with said pressure, and the hook is held properly positioned relatively to the screw and plate. As the screw is rotated to move the plate hook in a direction toward the plate the en- 35 gaging portion of said drop-in member slides along the engaged portion of the groove.

While I have herein shown and particularly described the preferred embodiment of my invention I do not wish to be limited 40 to the precise details of construction shown as changes may readily be made without departing from the spirit of my invention, but having thus described my invention I claim as new and desire to secure by Letters Patent the following:—

1. A plate hook having a drop-in member receivable in an undercut groove in a base and adapted to be turned in said groove to engage said drop-in member with the undercut 50 portions of the groove and having a plate holding hook member connected with the drop-in member, and means extending longitudinally of the groove and engageable with said plate hook and the side of said 55 groove to prevent the hook from turning to disengage said drop-in member from the undercut portion of the groove and along which said plate hook is adjustable.

2. A plate hook having a drop-in member 60 receivable in an undercut groove in a base and adapted to be turned in said groove to engage said drop-in member with the undercut portion of the groove and having an opening therein and having a plate holding 65 hook member connected with the drop-in

member, and means engageable with said opening and a side of the groove to prevent the drop-in member turning to disengage said drop-in member from the undercut portion of the groove.

3. A plate hook having a drop-in member receivable in an undercut groove in a base and adapted to be turned in said groove to engage said drop-in member with the undercut portion of the groove and having an 70 opening therein extending longitudinally of the groove when said drop-in member is engaged with said undercut portion and having a plate holding hook member connected with the drop-in member, and means disposed in said groove and extending longitudinally thereof and engageable with said opening and a side of the groove to prevent the hook from turning to disengage said drop-in member from the undercut portion 75 of the groove.

4. A plate hook having a drop-in member receivable in an undercut groove in a base and adapted to be turned in said groove to engage said drop-in member with the undercut portion of the groove and a plate holding hook member connected with the drop-in member, an adjustment screw extending longitudinally of said groove, and a mounting for said screw restricting the same as 90 to bodily movement relatively to said base and adapted to allow rotation of said screw, said screw being in screw threaded engagement with said plate hook to provide adjustment thereof longitudinally of the 95 groove and to prevent the same from turning to disengage said drop-in member from engagement with the undercut portion of the groove.

5. A plate hook having a drop-in member 105 receivable in an undercut groove in a base and adapted to be turned in said groove to engage said drop-in member with the undercut portion of the groove and a plate holding hook member connected with the drop-in member, and a screw for adjusting the plate hook longitudinally of the groove, the shank of the screw being in threaded engagement with the plate hook, the screw having a head engageable with the base at 110 different places along the groove.

6. A plate hook having a drop-in member receivable in a diagonally arranged undercut groove in a base and adapted to be turned in said groove to engage said drop-in member with the undercut portions of the groove and having said drop-in member engageable with an opposed side of the undercut portion of the groove when said drop-in member is turned into engagement with 115 the undercut portion thereof and having a plate holding hook member connected with said drop-in member, and means for adjusting said plate hook longitudinally along 120 said groove in a direction to cause a wedg- 125 130

ing action of said plate hook between an engaged plate and said engaged side of the undercut portion of the groove.

7. A plate hook having a drop-in member 5 receivable in a diagonally arranged undercut groove in a base and adapted to be turned in said groove to engage said drop-in member with the undercut portions of the groove and having said drop-in member engageable 10 with an opposed side of the undercut portion of the groove when said drop-in member is turned into engagement with the undercut portion thereof and having a plate holding hook member connected with said 15 drop-in member, and an adjustment screw engageable with said plate hook when said plate hook is turned to engage said drop-in member with said undercut portion and adapted to be operated to adjust the plate 20 hook longitudinally of said groove in a direction to cause a wedging action of said plate hook between an engaged plate and said engaged side of the undercut portion 25 of the groove.

8. A plate hook having a drop-in member

receivable in a diagonally arranged undercut groove in a base and adapted to be turned in said groove to engage said drop-in member with the undercut portions of the groove and having said drop-in member 30 engageable with an opposed side of the undercut portion of the groove when said drop-in member is turned into engagement with the undercut portion thereof and having a plate holding hook member connected 35 with said drop-in member, and a screw for adjusting the plate hook longitudinally of the groove in a direction to cause a wedging action of said plate hook between an engaged plate and said engaged side of the 40 undercut portion of the groove, the shank of the screw being in threaded engagement with the plate hook, the screw having a head engageable with the base at different places along the groove. 45

In witnesses whereof I hereunto subscribe my name this 24th day of February, A. D., 1917.

ROBERT MIEHLE.
